UNITED STATES PATENT OFFICE.

SVEN JULIUS STRID, OF CHICAGO, ILLINOIS, ASSIGNOR TO FRED MATHEWS, OF CHICAGO, ILLINOIS.

HAND-BRAKE BOOSTER.

Application filed May 2, 1925. Serial No. 27,588.

My present invention relates to gearing and more particularly to a geared structure for operating the brakes on railway cars, although the structure may be used for other 5 purposes or wherever its principles may be found advantageous.

In freight cars and similar vehicles where hand brakes are used it is well known that there is usually slack in the chains, rods, 10 and levers that must be taken up before the brake-shoes are brought into contact with the wheels. To take up this slack as well as to apply the initial pressure of the shoes against the wheels requires very little effort 15 as compared to the power necessary to tighten the shoes sufficiently to render their braking action effective upon the moving wheels. Usually it has been the practice for the brakeman to give the wheel on the brake- 20 mast a "spin" to take up the slack and thereafter to pull on the wheel with his greatest effort to set the brakes.

My geared structure is especially designed to be applied to the brake mechanism of a 25 railway car and is so constructed that only a slight rotative movement of the brake-wheel is necessary to take up the slack and thereafter the gear ratio changes so that with the same or slightly less force than is 30 usually required a greater pressure is exerted by the shoes against the wheels.

The device is compact and simple in construction, is made from few parts, and is novel and dependable in operation.

35 I prefer to carry out my invention and accomplish its divers objects in substantially the manner hereinafter fully described and as more particularly pointed out in the claims, reference being made to the accompanying drawings that form a part of this 40 specification.

In the drawings:—

Fig. 1 is a top plan of my invention showing it applied to a railway car brake.

45 Fig. 2 is a side elevation of the structure shown in Fig. 1.

Fig. 3 is a transverse section on line 3—3 of Fig. 2 and drawn to a larger scale.

50 Fig. 4 is a schematic top plan of my device detached and drawn to an enlarged scale. In this view the parts are illustrated in their relative positions at the beginning of their movement.

55 Fig. 5 is a view similar to Fig. 4 showing the relative positions of the parts when the

greatest power is being applied to the brake-shoes.

Fig. 6 is a face view of one end of the reciprocal rack.

In the drawings, which illustrate a typical or preferred embodiment of my invention, I have employed the same reference characters to designate corresponding parts wherever the same appear throughout the several views.

Secured to one of the longitudinal sills 10 of the car underframe is a carrier for the gear device in the form of a U-shaped casting that is set sidewise (Fig. 2) and is supported by horizontal straps 11 and inclined 60 bracing straps 12 that are bolted or otherwise secured at their end to the sill. The upper member of the U-shaped casting is a substantially flat rectangular plate 13 the outer edge of which is provided with a depending flange 14 of a J-shape section and spaced from this flange and above the hook 65 end of the J is a rib 15 that alines vertically therewith so that there is provided a guideway or guide channel 16 for the reciprocal rack which will hereinafter be described in detail. The connecting member 17 of the U-shaped casting is preferably vertically disposed and extends downwardly from the 70 forward edge of the plate 13 and from the lower edge of this member the other horizontal member of the U-shaped casting extends rearwardly under the plate in the form of a tapered bracket 18 that terminates centrally of the plate 13 where it is provided 75 with a bearing boss for the spindle 19 of the pinion that coacts with the rack above mentioned. At the rear outer corner of the plate 13 there is a tubular extension 20 the interior 80 of which is shaped similar to the guideway or channel to receive the rack, and the outer edge of this extension is provided with a 85 concave seat 21.

Rotatably mounted on the spindle 19 is 90 the gear member 22 of substantially a scroll outline and provided with the peripheral teeth, while the hub 23 which is elongated below the member 22 has a winding drum 24 secured to it to which the adjacent end of the chain is anchored.

100 The teeth 26 on the edge of the gear member 22 between the points A and B (Figs. 4 and 5) are arranged concentric to the axis of the member and the axis of rotation thereof thus providing a segmental gear.

and the teeth 27 between the points B and C (Figs. 4 and 5) are arranged in a convolute and are eccentric to said axis, so that the whole member may be said to be of the scroll gear type.

The gear member that coacts with the one just described comprises a reciprocable rack in the form of an elongated bar 28 having teeth upon one edge and having a T-shaped flange 29 extending along its edge opposite the teeth that fits the guide channel 16 heretofore alluded to. The teeth 30 on the rack between the outer rear end D thereof and the point E are parallel with the opposite edge of the rack bar and are coactable with the concentric teeth 26 on the scroll gear, and from the point E the toothed edge of the rack takes a concave curve towards gear members 22 and has teeth 31 between the point E and the end F of the rack that are coactable with the convolute teeth 27 on the scroll gear member.

The initial positions of the gear members are illustrated in Fig. 4 where the inner end C of the convolute or eccentric set of teeth 27 are engaged with end F of the curved set of rack teeth 31 and when the rack is moved to the right in the direction of the arrow (Fig. 4) the maximum ratio between the gear members is effective and the gear 22 is rotated rapidly to take up all slack and lost motion in the chain levers, rods and the like. This maximum ratio gradually reduces during the longitudinal movement of the rack in the direction of the arrow until the concentric set of teeth 26 between the pivots A-B on the scroll gear are engaged with the longitudinal parallel set 30 of the rack between the points D-E thereof, which reduces the ratio to a minimum, but the force that is then being applied to the winding drum 24 has been greatly increased over what it was when the gear was driven faster by the rack during initial movement.

The forward end of the rack element is provided with a bifurcation 32 between the arms of which the adjacent end of the pull rod 33 is pivotally connected by a bolt 34, and back of the bifurcation the web of the rack member is cut down as at 35 to provide a recess into which the wide edge of the gear member 22 may be positioned as will be understood from the detail in Fig. 4. The opposite end of the rack bar is reduced as at 36 and is threaded to receive a flanged or cup-washer 37 that is held in place by a nut 38 screwed onto the reduced end 36, and interposed between the washer 37 and the concave seat 21 of the casting extension is a coiled expansion spring 39 that surrounds the straight portion of the rack that projects rearwardly through the tubular extension 20 so that when the pull has been released on bar 33 the spring 39 will automatically return the gear elements to their normal or

initial position as designated in Fig. 4. The forward end of the pull rod is connected in any manner to the brake mast at the end sill of the car and the rear end of chain 25 is suitably connected to the rocking brake lever 40 at the end of the latter nearest the air-brake cylinder 41, but it will be understood that other methods of mounting the same may be devised to suit any particular installation.

It is obvious that numerous changes or modifications of the structure herein shown may be made without departing from the principles involved, and I desire it understood that the same are fully contemplated as coming within the scope of the appended claims.

What I claim is:

1. A hand-brake booster comprising a brake pull-rod, a carrier, a driven scroll gear 85 rotatably mounted therein, a guideway on said carrier, a driving rack reciprocable in said guideway the teeth of which are arranged to constantly mesh with the teeth of said gear, one end of said rack connected with said pull-rod and the opposite end being extended beyond said guideway, and a spring one end of which is engaged with the extended portion of said rack and the opposite end is engaged with a portion of said carrier, whereby to automatically return said elements to normal positions.

2. A hand-brake booster comprising a brake pull-rod, a carrier, a driven scroll gear rotatably mounted therein, a guideway 100 on said carrier, a driving rack reciprocable in said guideway the teeth of which are arranged to constantly mesh with the teeth of said gear, one end of said rack connected with said pull-rod and the opposite end being extended beyond said guideway, and a coiled spring surrounding the extended end of said rack and one end of which is engaged with the extended portion of said rack and the opposite end is engaged with a portion of said carrier whereby to automatically return said elements to normal positions.

3. A hand-brake booster comprising a brake pull-rod, a carrier of substantially 115 U-shape, a driven gear rotatably mounted between opposite members of said carrier, a guideway extending laterally from one of the members of the carrier, a driving rack reciprocable in said guide in mesh with said gear, said rack projecting at one end beyond the guideway and at its opposite end connected with said pull-rod, an abutment upon the outer end of said rack, and a coiled spring surrounding said rack between said abutment and the adjacent end of the guideway, whereby the rack, pull-rod and gear are automatically returned to normal position after each movement opposite to the tension of said spring.

4. A hand-brake booster comprising a brake pull-rod, a longitudinally reciprocable driving gear member connected with said rod and consisting of a rack having a terminal ¹⁵ toothed portion curved away from the plane of its main portion, a driven gear member consisting of a segmental gear of concentric outline engageable with the main portion of the rack and an eccentric gear extending ¹⁰ inwardly towards the axis of the segmental gear and engageable with the curved por-
- tion of the rack, a guide structure through which a portion of the driving member projects, and means connected to the projecting portion of the driving member for automatically returning the gear members and said pull-rod to normal positions.

Signed at Chicago, in the county of Cook, and State of Illinois, this 27th day of April, 1925.

SVEN JULIUS STRID.
